Attorneys

UNITED STATES PATENT OFFICE.

EDGAR S. COWAN, OF HARVEY, ILLINOIS.

FLEXIBLE TROWEL.

Application filed May 18, 1925. Serial No. 31,146.

To all whom it may concern:

Be it known that I, EDGAR S. COWAN, a citizen of the United States, residing at Harvey, in the county of Cook and State of Illinois, have invented certain new and useful Improvements in Flexible Trowels; and I do declare the following to be a full, clear, and exact description of the invention, such as will enable others skilled in the art to 10 which it appertains to make and use the same.

When applying a finishing coat of cement or plaster to a rough wall, such as one which has been poured between forms, difficulty is very often experienced with the ordinary trowels commonly used, particularly when applying the cement or the like to walls having a multiplicity of projecting gravels or the like. It is the object of my 20 invention however, to provide a flexible trowel of special construction, including a plurality of closely spaced spring fingers disposed in a common plane, any one or group of said fingers being adapted to yield 25 independently of the others as they pass over rough surfaces.

Another object of the invention is to provide a trowel of the general form above referred to, but having the free ends of its 30 fingers specially formed to produce either a ribbed or grooved finish to the work, or to impart some other desired design thereto.

With the foregoing in view, the invention resides in the novel subject matter hereinafter described and claimed, the description being supplemented by the accompanying drawing.

Figure 1 is a side elevation partly broken away and in section, showing one form of trowel constructed in accordance with my 40 invention.

Figure 2 is a vertical transverse sectional view as indicated by line 2-2 of Fig. 4.

Figure 3 is a side elevation of a portion 45 of a trowel, showing a different form of finger construction.

In the drawing above briefly described, the numeral 1 designates a handle which may be of any desired design, the handle shown being very similar to a paint brush handle and having an elongated back portion 2 at the inner end of the hand grip, this back portion being preferably provided with a longitudinal kerf 3, for a purpose 50 to appear.

Projecting in a common plane from the

back portion 2 of the handle 1, are a number of closely spaced spring fingers 4 of uniform lengths. These spring fingers are preferably formed from a single spring 60 metal plate 5, by forming the latter with parallel slits, 6 from one edge to a line spaced from its opposite edge, and the unslit portion of the plate is preferably secured in the kerf 3, by appropriate fasteners 65 7 passing through the plate and the back portion 2.

The three ends of the fingers 4 may be straight and in alinement with each other as shown in Fig. 1, or they may be shaped 70 to impart an undulating edge to the trowel. One way of accomplishing this, is to form notches 8 in the free ends of the fingers, as disclosed in Fig. 3, and when this is done, it will be obvious that wherever the 75 trowel is moved over the cement being applied, it will leave a rib and groove formation to the completed work, so that very artistic results may be obtained and possibly, various designs worked out. 80

By using the improved trowel, very rough walls may be plastered with cement or ordinary plaster with ease, as any of the fingers 4 or any group of such fingers may yield 85 with respect to the others, as they encounter numerous imperfections. In using the device, the plastic cement or the like with which a wall or other surfaces is to be coated, may be taken from a mortar board or the like by means of the improved trowel, conveyed to the surface to be plastered, by such trowel, and applied to said surface by proper manipulation of the trowel. When spreading the plastic upon the surface, the trowel is so held that the spring fingers 90 are disposed in a plane at an acute angle to said surface, and the tool is of course moved in such a direction that the free ends of the spring fingers 4 trail along upon the plastic and apply it effectively. 95

Excellent results have been obtained from a device constructed substantially in accordance with the present disclosure, but it is obvious that the invention is not restricted to the particular form of trowel shown, 100 as obviously, it might be fashioned after an ordinary plasterer's trowel, transversely slit from its edges toward its central portion to divide it into a multiplicity of resilient fingers. 105

I claim:

1. A plastering trowel comprising a han-

dle, and a plurality of flat closely spaced spring fingers projecting therefrom in a common plane, any one or group of said fingers being adapted to yield independently of the others when passing over rough portions of the wall being plastered.

2. A structure as specified in claim 1; said fingers being formed by slitting a resilient plate from one edge to a line near its other edge, said handle having a kerf

in which the un-slitted portion of the plate is secured.

3. A structure as specified in claim 1; said fingers having their free ends shaped to produce an undulating edge for the trowel, 15 adapted to impart a special finish to the work.

In testimony whereof I have hereunto affixed my signature.

EDGAR S. COWAN.
